Des. 193,375
Patented Aug. 7, 1962

193,375

HAIR TREATING APPLICATOR

Albert Safianoff, 6142 N. Avers, Chicago, Ill.

Filed July 27, 1961, Ser. No. 66,094

Term of patent 14 years

(Cl. D86—10)

Fig. 1.

Fig. 2.

Fig. 3.

Fig. 4.

FIG. 1 is a top plan view of a hair treating applicator showing my new design;

FIG. 2 is a view in side elevation;

FIG. 3 is a view in front elevation; and

FIG. 4 is a view in rear elevation.

The broken line showing of the upper portion of a bottle in FIG. 2 is for environmental illustrative purposes only.

I claim:

The ornamental design for a hair treating applicator, as shown and described.
